G. E. McFADDEN

CEILING LIGHT FOR LIGHTING FIXTURES

Filed Oct. 14, 1922

Glenn E. McFadden INVENTOR

By Rodman Poe, his ATTORNEYS

UNITED STATES PATENT OFFICE.

GLENN E. MCFADDEN, OF LAKEWOOD, OHIO, ASSIGNOR TO ALFRED VESTER SONS, INC.,
OF PROVIDENCE, RHODE ISLAND, A CORPORATION OF RHODE ISLAND.

DESIGN FOR A CEILING LIGHT FOR LIGHTING FIXTURES.

Application filed October 14, 1922. Serial No. 3,966. Term of patent 14 years.

To all whom it may concern:

Be it known that I, GLENN E. MCFADDEN, a citizen of the United States, and residing at Lakewood, in the county of Cuyahoga and State of Ohio, have invented a new, original, and ornamental Design for a Ceiling Light for Lighting Fixtures, of which the following is a specification, reference being had to the accompanying drawing, forming part thereof.

Fig. 1 is a side view of a ceiling light for lighting fixtures, showing my new design; Fig. 2 is a plan view of the same.

I claim—

The ornamental design for a ceiling light for lighting fixtures, as shown.

GLENN E. MCFADDEN.
